UNITED STATES PATENT OFFICE.

THOMAS A. MCGRANAHAN, OF NEWHALL, IOWA.

HAME-TUG.

SPECIFICATION forming part of Letters Patent No. 352,626, dated November 16, 1886.

Application filed August 14, 1886. Serial No. 210,914. (No model.)

To all whom it may concern:

Be it known that I, THOMAS A. MCGRANAHAN, of Newhall, in the county of Benton and State of Iowa, have invented certain new and useful Improvements in Hame Tugs; and I do hereby declare the following to be a full, clear, and exact description of the invention, such as will enable others skilled in the art to which it pertains to make and use it, reference being had to the accompanying drawings, which form part of this specification.

My invention relates to an improvement in hame-tugs; and it consists in the combination of the draft-rod having an attachment upon its front end to connect it with the hame, the U-shaped rod, which is loosely connected to the draft-rod, and upon which the springs are placed, the rod which is connected to the tug-buckle, the plate or plates against which the ends of the springs bear, and the strap which is applied to the inner sides of the different parts, so as to prevent them from injuring the horse, all of which will be more fully described hereinafter:

The object of my invention is to provide a spring attachment which is to be connected directly to the hame, so that the strain in starting will be applied gradually to the horses, and thus prevent them from becoming hurt or injured in any way, and making it easier for them to start a load.

Figure 1 is an edge view of a device embodying my invention. Fig. 2 is a side elevation of the same.

A represents the draft-rod, which is provided with a loop, B, upon its front end for the attachment to the hames. The rear end of this rod A is connected loosely to the U-shaped rod C, upon the prongs of which the two springs D are placed.

Over the screw-threaded ends of the two prongs of the rod C is passed a bearing-plate, F, against which the ends of the springs bear. This plate can be adjusted back and forth upon the prongs of the rod C by means of the nuts F', for the purpose of increasing or decreasing the tension of the springs, as may be desired. Also, passed over the prongs of the rod C is a plate, H, which bears against the

front ends of the springs, and to which plate 50 is rigidly connected the rod I, which is connected at its rear end to the tug buckle or loop L. Secured to this rod is a cross-plate or ears, N, to which the strap P is rigidly secured at this point. When the draft comes upon the 55 rods A, C, and I, the draft is transferred by the sliding movement of the rods upon the springs until the springs have become compressed to their greatest degree, when the draft again falls upon the rods. As the rods give under 60 the compression of the springs the draft is gradually brought to bear upon the hames, and through them upon the horse's shoulders, without any jerk or jar to the horse. As the 65 springs are gradually compressed the strain of starting the load is gradually brought to bear upon the horse's shoulders, and thus the starting of a load is made much easier in every respect.

Secured to the inner side of the devices is 70 the strap P, which is sufficiently wide to prevent any of the parts coming in direct contact with the horse and thus injuring him. The front end of this strap is provided with a guiding-loop, S, which catches over the draft-bar and allows the front end of the strap to move freely back and forth as the device becomes lengthened or shortened while in operation. By means of this construction the strap is prevented from doubling, and thus 75 80 chafing and rubbing the horse by the movement of the parts to which the strap is connected. At the other end of this device the strap is rigidly connected to different parts at two different points, so that the front end alone 85 allows the movable parts to adjust themselves in relation to it.

Having thus described my invention, I claim—

1. The combination of a draft attachment, 90 constructed substantially as shown and described, with a strap which is immovably fastened to the device at one end, and which is provided at the other end with a loop for the draft-rod to pass through, substantially as 95 shown.

2. The combination of the draft-rod provided with a loop upon its front end for at-

tachment to the hame, the U-shaped rod, which is loosely connected to the draft-rod, the movable plate for the ends of the springs to bear against, the adjusting-nuts, and the 5 rod I, which has a tug-buckle attached to its rear end and a plate for the springs to bear against secured to its front end, substantially as shown and described.

In testimony whereof I affix my signature in presence of two witnesses.

THOMAS A. MCGRANAHAN.
